UNITED STATES PATENT OFFICE.

EDWARD F. REYNOLDS, OF ASHLAND, WISCONSIN.

DISCHARGE APPARATUS FOR PIVOTED SPOUTS.

SPECIFICATION forming part of Letters Patent No. 570,055, dated October 27, 1896.

Application filed July 10, 1896. Serial No. 598,670. (No model.)

To all whom it may concern:

Be it known that I, EDWARD F. REYNOLDS, a citizen of the United States, and a resident of Ashland, in the county of Ashland and 5 State of Wisconsin, have invented certain new and useful Improvements in Discharge Apparatus for Pivoted Spouts; and I do hereby declare that the following is a full, clear, and exact description thereof.

10 My invention relates to certain improvements in the class of apparatus such as is used especially on docks for the transfer to vessels of ore and coal, though not restricted to such use; and it consists in certain peculiarities of construction and combination of parts, as will be fully set forth hereinafter, and subsequently claimed.

15 In the drawings, Figure 1 is a side elevation, partly broken away, of a structure embodying my invention. Fig. 2 is a front elevation of the same with the spout or chute in a horizontal position. Fig. 3 is a detail view, partly in section, on the line 3 3 of Fig. 1. Figs. 4 and 5 are detail sectional views on the 25 lines 4 4 and 5 5, respectively, of Fig. 2. Fig. 6 is a detail sectional view on the line 6 6 of Fig. 4.

20 Referring to the drawings, A represents a bin or dock-pocket, of ordinary construction, to hold ore, coal, or other material, supported in the usual manner upon or above a dock. B B are the side timbers of a frame (usually called a "gallows-frame") secured to the front vertical timbers b b of the bin or 35 pocket A.

30 C is the spout or chute, whose lower end is pivotally secured to ears a a, projecting from said timbers b b.

35 D D are the spout-operating cables, whose 40 ends are secured to the upper projecting ends of a yoke or strap c, near the outer end of the spout C.

45 E E are free-running grooved guide-pulleys, secured to the outer ends of a shaft or axle d, which passes transversely through the side timbers B of the gallows-frame. F F are other 50 free-running grooved guide-pulleys, mounted in brackets e e, secured to the lower front transverse timber f of the bin or pocket A.

55 G is a front cross-piece rigidly secured to the central front support g of the bin or pocket A, and H is a rear cross-piece rigidly secured

to the central rear support h of said bin or pocket. Brackets i i, carrying free-running guide-pulleys I I, are secured to the cross-piece G adjacent to its ends, and headed bolts J J extend through said cross-piece G and the vertical arms of the brackets i i, the heads of said bolts on the inner side of the cross-piece G being each provided with two eyes j k, 60 one above the other. Eyebolts K K extend through the rear cross-piece H, near each end thereof, the eyes being on the inner ends of said bolts and their outer ends being screw-threaded to receive handled adjusting-nuts 65 m m to regulate the tension of suspension-cables M M, which extend between and are fastened to the eyes of the bolts K K and the lower eyes k k of the bolts J J.

70 L L are counterweights, from which rise angular straps n n, between which straps are pivoted grooved pulleys N and O. The pulleys N are just above the tops of the counterweights L and are adapted to receive and run upon the suspension-cables M, while the pulleys O are between the extreme upper and forwardly-bent ends of the straps n n and are for the reception of the spout-operating cables D, which are arranged as follows: There are two of these cables and the upper end of 80 each is secured, as stated, to the opposite ends of the yoke or strap c, near the outer end of the spout or chute C. From thence the said cables pass upward over and around the pulleys E E, and thence downward beneath the pulleys F F and back, beneath the bin or pocket A, to and around the pulleys O O on the counterweights L L, and thence forward to the upper eyes j j of the bolts J J on the cross-piece G, and there these ends are 90 secured.

95 P P represent the drums of a winch p, journaled in the side pieces B B of the gallows-frame, which winch is provided with a friction-brake q and ratchet-wheel r, the latter controlled by a dog or pawl s. Hinge-clutches Q Q are secured to the side pieces of the gallows-frame to control the cables D D, which pass through them, said clutches having each a screw-nut with handle, whereby the cable 100 can be readily clamped at any time, as best shown in Fig. 6. R R are small chains connected to the drums P P of the winch, and secured to the lower ends of these chains are

light cables S S, which pass down in front of the structure and under pulleys II and thence back to the counterweights LL, to which they are fastened, as shown at *t t* in Figs. 1 and 2.

5 The operation of my device will be readily understood from the foregoing description of its construction, taken in connection with the accompanying drawings.

The normal position of the parts is shown 10 in Fig. 1 with the spout or chute C raised. Now by turning the crank of the winch *p* the small chains R R are wound up on the drums PP, and this action draws up the light cables S S and causes the counterweights LL, 15 to which said cables S S are attached, to travel forward and upward on the inclined suspension-cables MM, and thus as the loop in the cables DD, which is around the pulleys OO, carried by said counterweights, moves forward 20 and upward the outer end of the spout or chute C will automatically move forward and downward by its own weight as fast as the forward movement of the said counterweights LL will permit, and said counterweights as 25 they rise upward will serve to equalize the increasing weight and pressure of the downward-descending spout or chute. When the spout or chute is down to the required point, (indicated by the dotted lines in Fig. 1,) the 30 ratchet-dogs will hold it in position, while the hinge-clutches QQ are adjusted tightly on the cables to hold the spout or chute rigidly in position.

In order to restore the spout or chute to its 35 original position, it is only necessary to release the clutches and throw off the ratchet-dog, when the reverse movement of the counterweights LL down the inclined suspension-cables MM will automatically raise the spout 40 or chute. By the inclined arrangement of the suspension-cables M and the travel of the counterweights L thereon in either direction the uneven strain of the spout or chute occasioned by the different angles it assumes 45 in its descent and ascent is always equalized and the unequal resistance overcome.

Having thus described my invention, what I claim as new, and desire to secure by Letters Patent, is—

50 1. In a discharge apparatus for pivoted spouts, the combination with a suitable support, of an inclined suspension-cable, a counterweight adapted to travel thereon, an ad-

ditional free-running guide-pulley mounted on said counterweight, a series of free-running guide-pulleys mounted on said support 55 at the front thereof, a spout pivoted to said support, and a cable secured to the outer end of said spout, and passing around said series of pulleys, and around the additional 60 pulley on the counterweight, and thence brought forward and secured to the support at the front thereof, in line with the said series of pulleys, whereby the spout will be automatically raised by the downward travel 65 of the counterweight on the inclined suspension-cable.

2. In a discharge apparatus for pivoted spouts, the combination with a suitable support, of inclined suspension-cables, counterweights adapted to travel thereon an extra 70 guide-pulley on each counterweight, a spout pivoted to said support, free-running guide-pulleys on the support, cables connected to the outer end of the spout and to the support 75 beneath the pivotal point of the spout, and passing around the free-running guide-pulleys on the support and counterweights, a winch on the support, and chain or cable connection between the drums of said winch 80 and the traveling counterweights, whereby the winding of the chain or cable on the drums will draw the counterweights up the inclined plane of the suspension-cables, and permit the spout to automatically move forward and downward by gravity, as the said 85 counterweights ascend.

3. In a discharge apparatus for pivoted spouts, the combination with a suitable support and a spout pivoted thereto, of inclined 90 suspension-cables, and double-acting traveling counterweights moving thereon, free-running guide-pulleys mounted on the support and counterweights and cables connected at their forward ends to said spout and passing around said guide-pulleys, the other ends of said cables being secured to said support. 95

In testimony that I claim the foregoing I have hereunto set my hand, at Ashland, in the county of Ashland and State of Wisconsin, in the presence of two witnesses.

EDWARD F. REYNOLDS.
